CARBURETOR

Filed March 10, 1924

Stanley M. Udale.

UNITED STATES PATENT OFFICE.

STANLEY MARTIN UDALE, OF DETROIT, MICHIGAN, ASSIGNOR TO GEORGE M. HOLLEY, OF DETROIT, MICHIGAN.

CARBURETOR.

Application filed March 10, 1924. Serial No. 698,036.

The object of this invention is to devise an improved variable Venturi carburetor adapted for an internal combustion engine of the automobile type.

5 The figure shows clearly in cross sectional elevation all the elements of the invention arranged (for the purpose of illustration) in one plane.

In the figure A is the air entrance, B is the 10 Venturi tube, C is a streamlined obstruction supported by the spring D and operated indirectly by the butterfly throttle G. H is a conventional float chamber adapted to maintain the fuel at a more or less constant level 15 and having a restricted outlet I controlled by a needle valve J. K is a horizontal fuel passage leading to the main fuel nozzle L, which discharges into a primary mixture chamber M.

20 N, O, and P are rich mixture outlets from M into the throat of the Venturi tube B. Q is the auxiliary air vented reservoir and S is the low speed tube communicating with the mixture outlets at T and U adjacent to and 25 in advance of the throttle valve G.

The cylinder V in which the piston E reciprocates is provided with a restricted air vent W communicating with the atmosphere. The spring D is supported by a bracket X. 30 The space between the throttle G and the obstruction C is lettered Y.

Operation.—When the throttle is first moved from the closed position the fuel outlets T U function in a well known manner. 35 On further opening of G the piston E moves down because the atmospheric pressure acting on its upper surface is greater than the pressure in Y. W being a #60 orifice—.04" diameter, the travel downwards of E and C is 40 relatively slow and steady.

Momentarily there is created between C and B a zone of intense velocity resulting in the violent aspiration of fuel through N from L. If the throttle is held in the position shown the engine speeds up and the obstruction moves down and air is admitted more freely, and the depression acting on L through N is reduced.

On again moving the throttle the depression again increases momentarily, this time 45 opposite the passage O, and the richness of the mixture is temporarily greater followed by a normal running mixture. In this way the tendency for the air to "get ahead" of the fuel is checked and the reverse result is 50 obtained.

As the obstruction C moves against the air stream it is possible to arrange a series of 55 openings N, O, P, which are progressively uncovered or rather subjected to the engine suction. The function of the fuel well Q and vent R is too well known to require discussion at this date.

What I claim is:—

In a carburetor, an air entrance, a mixture outlet, a Venturi tube, a fuel entrance therein comprising a plurality of fuel outlets, a stream-lined obstruction in said venturi located opposite said fuel entrance during normal operation, vacuum controlled means for 65 moving the obstruction against the air flow, whereby the fuel entrances are gradually and progressively subjected to the pressure existing in the venturi above the obstruction.

70 75 In testimony whereof he affixes his signature.

STANLEY M. UDALE.
